UNITED STATES PATENT OFFICE.

JACOB MARCUS, OF BOSTON, MASSACHUSETTS.

DESIGN FOR AN ALARM OR DRUM-SHAPED CLOCK HOUSING STAND.

46,346.

Specification for Design.

Patented Sept. 1, 1914.

Application filed July 3, 1914. Serial No. 848,971. Term of patent 3½ years.

To all whom it may concern:

Be it known that I, JACOB MARCUS, a citizen of the United States, and residing at Boston, in the county of Suffolk and State of Massachusetts, have invented a new, original, and ornamental Design for an Alarm or Drum-Shaped Clock Housing Stand, of which the following is a specification, reference being had to the accompanying drawing, forming part thereof.

In the drawing, Figure 1, is a front view

of an alarm or drum-shaped clock housing-stand, showing my new design. Fig. 2 is a side view of Fig. 1. Fig. 3, is a sectional view taken on line 3—3 in Fig. 2.

I claim:

The ornamental design for an alarm or drum-shaped clock housing-stand, as shown.

JACOB MARCUS.
